UNITED STATES PATENT OFFICE.

CATHARINE A. GRISWOLD, OF NEW YORK, N. Y.

DESIGN FOR THE ORNAMENTATION OF CORSETS.

SPECIFICATION forming part of Design No. 18,923, dated February 12, 1889.

Application filed January 4, 1889. Serial No. 295,477. Term of patent 14 years.

To all whom it may concern:

Be it known that I, CATHARINE A. GRISWOLD, of the city of New York, county and State of New York, and a citizen of the United States, have invented and produced a new and useful Design for the Ornamentation of Corsets, of which the following is a full, clear, and exact description, reference being had to the accompanying drawing, forming part of this specification.

The single figure in the drawing represents in side elevation a corset containing my invention.

The leading and special feature of my new design consists in two bands extending from the upper edge of the corset downwardly to the waist-line thereof and two bands or stripes extending from the lower edge of the corset upwardly to the said waist-line thereof, of the end of each of the bands or stripes extending from the upper edge meeting opposingly at said waist-line the end of the corresponding band or stripe extending from the lower edge and an edgewise-bent band or stripe at said waist-line and between and extending from the opposed ends of two of said corresponding bands on the waist-line to the opposed ends of the other two of said corresponding bands.

A represents a corset, which may be in the usual and ordinary form.

B and B' represent two bands or stripes which extend from the upper edge of the corset downwardly over the face of the same to the waist-line thereof.

C and C' represent two bands or stripes which extend from the lower edge of the cor-

set upwardly over the face of the same to the waist-line thereof.

The ends of the bands or stripes B and B' at the waist-line meet opposingly, respectively, the ends thereof of the bands or stripes C and C'.

D represents a band or stripe which is of comparatively short length, and which is given an edgewise bend. This edgewise-bent band or stripe D is placed at the waist-line of the corset and between and extending from the opposingly-meeting ends of the bands or stripes B and C to the opposingly-meeting ends of the bands or stripes B' and C'.

What I claim is—

The design for the ornamentation of a corset herein described and shown, the same consisting in two bands or stripes, B and B', extending from the upper edge of the corset downwardly to the waist-line thereof, and two bands or stripes, C and C', extending from the lower edge upwardly to the waist-line, the ends of the corresponding bands B and C at the waist-line meeting opposingly to each other, and the ends of the corresponding bands B' and C' at the waist-line likewise meeting opposingly, together with the edgewise-bent band or stripe D at said waist-line of the corset and between and extending from the opposingly-meeting ends of the bands B and C to the opposingly-meeting ends of the bands B' and C' thereof.

CATHARINE A. GRISWOLD.
